UNITED STATES PATENT OFFICE.

FRANK M. GODING, OF LIVERMORE FALLS, MAINE.

COUCH-ROLL LIFTER.

1,368,715.

Specification of Letters Patent. Patented Feb. 15, 1921.

Application filed October 28, 1919. Serial No. 334,019.

To all whom it may concern:

Be it known that I, FRANK M. GODING, a citizen of the United States, residing at Livermore Falls, in the county of Androscoggin and State of Maine, have invented 5 certain new and useful Improvements in Couch-Roll Lifters; and I do hereby declare the following to be a full, clear, and exact description of the invention, such as will 10 enable others skilled in the art to which it appertains to make and use the same.

This invention relates to an improved couch roll lifter and the principal object of the invention is to provide a lifter of the 15 character described which is so constructed that the screen may be put in place upon the lower couch roll without danger to the operator. In paper mills the machines are very often placed close together and with 20 the ordinary lifter it is necessary to climb upon an adjoining machine in order to put the screen in place but with this improved lifter it will not be necessary as the handle section is pivotally connected with the socket 25 section and therefore may be swung to one side.

Another object of the invention is to so construct this lever or lifter that the handle section may be releasably retained in alignment with the socket section, improved 30 latches being carried by the handle section and moving into sockets formed in the socket section.

Another object of the invention is to so 35 construct this lifter that it will be simple in construction and easy to operate.

This invention is illustrated in the accompanying drawing, wherein—

Figure 1 is a side elevation showing the 40 lifter applied to a couch roll,

Fig. 2 is an enlarged perspective view of the lifter,

Fig. 3 is a plan view of the lifter with one portion thereof shown in section.

This device is to be used in connection 45 with the lower couch roll 10 which rests in the open ended bearings 11, one of the spindles 12 of the roller being elongated as shown in Fig. 1. This lifter is provided 50 with a handle section 13 and a socket section 14, the handle section and socket section being provided with hinge extensions 15 and 16 through which extends the pivot pin 17 thus pivotally connecting the handle section 55 and socket section. The socket section in

addition to being provided with a main socket 18 is provided with smaller sockets 19 which are positioned upon opposite sides of the socket member and are adapted to receive the latching pins 20 which are slidably 60 mounted in the housings 21 and are provided with actuating pins 22 which not only permit the latching pins to be moved easily but limit their sliding movement in one direction. It will thus be seen that when the 65 latching pins are in the retracted position the handle section may be turned at right angles to the socket section but that this handle section may be secured in alignment with the socket section by extending the 70 latch pins so that they fit into the sockets 19. Notches 23 are provided in the socket member upon opposite sides thereof and are adapted to receive the ends of the fork 24 of the jack 25 which will be used in connection 75 with this couch roll lifter. By providing these notches to receive the ends of the fork, the socket member will be prevented from turning in the fork, and therefore the lifter cannot move out of the desired position when in use. 80

When in use the socket member will be placed upon the elongated spindle 12 with the handle member extending at substantially right angles to the socket member and 85 the jack will then be put in place and brought into engagement with the socket member. The jack will then be raised to lift the spindle off of the bearing and the screen then slipped over the handle section. The 90 handle section will then be extended in alignment with the socket section and will be locked in this extended position. The screen then can be put in place in the usual manner after which the lifter will be removed. It 95 will thus be seen that with this construction it is not necessary to climb upon an adjoining machine. It will be further noted that the screen may be carried down the aisle between the machines by passing the handle 100 through the roll of screen and after the socket has been pushed in place upon the spindle the handle is swung to the extended position or in alignment with the sockets. This will make the handling of the screen 105 very easy and further will prevent danger of the screen being damaged.

What is claimed is:—

1. A couch roll lifter having a handle section, a socket section pivotally connected 110

with the handle section, and means for releasably holding the handle section in alignment with the socket section.

2. A couch roll lifter comprising a handle section and a socket section pivotally connected with the handle section.

3. A couch roll lifter comprising a handle section, a socket section pivotally connected with the handle section, and provided upon 10 opposite sides of its pivotal connection with sockets, and securing pins slidably connected with the handle extension for extending into

the sockets to releasably hold the handle section in alignment with the socket section.

4. A couch roll lifter comprising a handle 15 section, and a pivotally mounted socket section provided with jack receiving notches upon opposite sides of its pivot point.

In testimony whereof I affix my signature in presence of two witnesses.

FRANK M. GODING.
